POLE REINFORCEMENT

Robert L. Allen, Buffalo, N. Y.

Application July 31, 1935, Serial No. 34,039

12 Claims. (Cl. 20—99)

My improvement relates generally to pole reinforcements and more particularly to reinforcements for wooden poles.

It is well known that poles set in the ground are especially subject to deterioration and decay in the immediate vicinity of the ground, while the remaining portions of such poles, from a short way above the ground, remain in substantially good and usable condition. This characteristic of poles is the cause of much trouble and expense. This is particularly true of the wooden poles used by the electrical industry, which poles are employed for supporting wires. When this decay and deterioration occurs, the poles are weakened at the point of the greatest strain. In order to remedy this condition, the methods used require large expense and the work of such repair is frequently dangerous, but is essential in order that the pole systems may be maintained in proper condition.

There have been a multitude of devices designed, tried, experimented with, and some patented, to overcome the difficulties mentioned, but these have not gone into general and extensive use owing to various inherent defects, such as high first cost, lack of adaptability to irregular shapes and sizes of poles, and clumsy appearance when installed. Another disadvantage of many of the devices thus tried and patented is that they present protruding shapes, such as bulges, lugs, and ribs which may and frequently do cause damage to vehicles brushing against them, as well as to the clothes of persons coming in contact therewith. These last mentioned disadvantages are especially vital to concerns engaged in electrical distribution, since the nature of their business requires the most careful regard for public safety and goodwill.

In order to overcome the disadvantages and objections above noted, and likewise to remedy in an inexpensive way the effects of decay and deterioration, I have produced my invention. The objects of my invention are to overcome the difficulties already mentioned and to provide a safe, substantial, strong, and relatively inexpensive means for effectually reinforcing poles.

The above objects and advantages have been accomplished by the device shown in the accompanying drawings, of which:

Fig. 1 is a side elevation of a pole equipped with my invention.

Fig. 2 is a front elevation thereof.

Fig. 3 is a sectional view taken on the line 3—3 of Fig. 1.

Fig. 4 is an enlarged, fragmentary, sectional

view of the upper fastening means of my device showing a part of the through-bolt of my invention.

Fig. 5 is a fragmentary, sectional view of the lower fastening means of my device, also showing a through-bolt.

Fig. 6 is a perspective view of my lower spacer block.

Fig. 7 is a perspective view of my upper spacer block.

Fig. 8 is a perspective view showing my clamping means applied to the through-bolt when in place in the pole.

My invention primarily consists of a plurality of structural steel channels 10 preferably made of a corrosion-resisting alloy and each provided, as usual, with a web 10a and right-angled flanges 10b. These channels are secured in the manner hereinafter described to the poles 11. Each of these channels, as shown in Figs. 1 and 2, has the greater part of its length driven in close proximity to the side of the pole below the ground level, indicated at 12, the upper shorter portion of each of these channels being secured to the pole above the ground level. While I have shown in the drawings two channels applied to a pole (see Fig. 1), yet in practice it is frequently wise and sometimes necessary to apply, in similar manner as that indicated in the drawings, more than two such channels to the poles.

These channels are relatively long and narrow. They may be driven securely into the ground in close proximity to the poles by a suitable hammer. They are embedded in the ground a considerable distance alongside of the pole so that the greater part of their length is preferably below the ground, thus providing a new foundation for the pole. In practice, I have found that, to get the best results, such channels should be driven into the ground a distance about ten times their width. For example, a channel seven inches wide should be driven in the ground about seventy inches or more. This is an important feature of safety since the security of the fixture in the ground increases in much higher ratio than the depth of the footing in the ground.

Those skilled in the art of overhead construction ordinarily assume that the strength of footings or settings of this general type increases in proportion to the square of the depth in which they are embedded in the ground, and some engineers use an even higher exponent than that.

In my construction I employ spacers 14. These

spacers may be of two types, an upper spacer 14b and a lower spacer 14a, and they are secured between the pole and the channels in the manner to be hereinafter and more particularly described. One of the chief functions of these spacers is to transfer the resisting moment of the channels to the pole to which the channels are applied. The spacers may be castings or forged pieces. Preferably I make the face of 10 the casting which contacts directly with the pole curved in form and provided with serrations or sharp points 15 (see Figs. 6 and 7), or any other suitable gripping means which will firmly grip the pole when being pressed tightly against the 15 same. In some of the claims I refer to these spacers as "sector-shaped". A spacer 14b is used at the top part of each of the channels and a spacer 14a is arranged near the ground level of each of the channels, but preferably above the 20 decayed or deteriorated portion of the pole. The distance between these spacers and their intimate gripping contact with the pole at these widely separated points applies a large effective 25 resisting moment to the poles to which my device is applied.

The channels are provided with holes 26 where the spacers 14 are to be located and bosses 25 are provided on the spacers for engagement with these holes. Such engagement interlocks 30 the spacers and channels and prevents relative movement between these parts. The bosses of the spacers thereby take all the thrust and shearing action produced between the channels and the spacers. The bosses 25 of the spacers are 35 preferably provided with bolt holes 17 so that through-bolts 16 may be passed therethrough. Obviously, while I have shown for convenience the spacers a little narrower than the space between the flanges 10b of the channels, it is clear 40 that these spacers may be made to fit snugly between the said flanges and, therefore, be made to take substantially all the lateral thrust placed upon the channels.

Preferably, the bolt hole 17 of each of the 45 spacers is inwardly flaring (see Figs. 6 and 7) and is made slightly larger at its smaller diameter than the bolt, so that when and if the pole is swayed, the bolt passing through the hole will be relieved of substantially all lateral 50 shearing action or moment.

As clearly shown in Fig. 6, the lower, sector-shaped spacer 14a is provided with a depending portion 18. This portion 18 comprises a relatively thin plate part 19 having a bolt hole 21 therethrough, and two depending, interspaced, side lugs 20 arranged one on each side of the bolt hole 21 for engagement with the head of the bolt 28, hereinafter described. The plate part 19 is provided on the side opposite the flanges 60 with a circular boss 24. This boss is adapted to engage with an opening 27 formed in the channel web 10a when the boss 25 is in engagement with the hole 26 and it thus assists in taking some of the shearing action between the channel and the spacers. While the depending portion 18 is preferably provided on the lower, sector-shaped spacer 14a, it may, of course, if desired, be advantageously used on the upper spacer 14b.

When the parts are first assembled, I find it 70 advantageous to place a lower spacer 14a within each of the channels 10 with the bosses 25 and 24 thereof in engagement with the holes 26 and 27, respectively, of the channels. A bolt 28 is 75 then passed through the hole 21 of the boss 24

of each of these spacers and securely tightened in place so that initially the spacers are firmly secured to the webs of the channels, whereby they will not be moved out of place as the channels are being driven to place in the ground. 5 By so securing the parts together, the curved surfaces of the spacers 14a will engage the pole and any tendency of the pole to move in either direction will be resisted by the channels. Since the poles at their surfaces near the ground may be and are often soft, the provision of the flanges 20 of the depending portions 18 on the lower spacers 14a brings about advantageous results, since they increase the area of contact 10 of the spacers with the pole. After the channels have been driven to place with the lower spacers 14a in place, as just above pointed out, the upper spacers 14b are put into place and engaged with the upper ends of the channels, the boss 25 of each of the spacers engaging with the hole 26 at the top of the channel. With the parts in their final positions, holes are now bored 15 through the pole in registering positions with the holes 17 of the spacers. These holes may be drilled in any suitable way, care being taken 20 that each one of them registers with the hole of the oppositely arranged spacer. A through-bolt is now placed through the pole and through each pair of registering spacers, after which each 25 of them is tightened up so as to force the spacers against the pole. With the spacers 14a and 14b thus in place with their faces in contact with the pole, and with the through-bolts 16 also in place, the clamping pressure is spread over a wide surface area of the pole and thereby renders 30 the pole, thus reinforced, capable of withstanding a stress substantially equal to the full 35 strength of the channels.

The sector-shaped spacers perform several 40 advantageous functions in my invention. One advantage of using these spacers results from the fact that the spacers, being tightly held between the pole and the web of the channel, substantially reinforce the comparatively thin channel web 45 and thus help to keep it rigid to resist the strain of the swaying pole. Another advantage is that the spacers in the position described keep a large part of the length of the channels which is above the ground spaced apart from the pole, thereby providing air spaces allowing free air circulation and thus preventing some deterioration 50 of the pole by not permitting moisture to collect underneath the channels and thereby rot the wood of the pole. If the channels were tightly 55 hugging the pole, there would be but little air circulation between them and the pole, and there would be accumulated between the pole and the channels a great deal of moisture which would tend to deteriorate the parts of the pole covered by the channels. Another important function 60 performed by these sector-shaped spacers is that of securely gripping the pole by means of the serrated or roughened inside surface of the spacers or by the sharp points provided on their inside faces so that the pole and the spacers and 65 the channels are made substantially a unit and thereby strongly reinforce the pole.

In reinforcing poles, it frequently happens that the poles are not only decayed or deteriorated near the ground surface but also they are frequently found to be split or badly cracked. Therefore, it is advantageous to compress the split or cracked portions of the pole sufficiently 70 at least to prevent it from further cracking or splitting. By means of my invention I am able 75

to so clamp such split or cracked poles in a very simple and effective manner.

For this purpose, I may employ a length of wire 22 which I preferably loop around one end of the 5 through-bolt 16 so that the wire passes semi-circularly in its looped condition around half of the pole and the two ends of the wire 22 are brought over the opposite protruding end of the through-bolt 16 and there, with suitable pinchers 10 or other device, the ends of the wire are twisted together until they are securely clamped over the through-bolt and at the same time the looped wire is brought to a high tension over half the circumference of the pole. In like manner, another 15 looped wire is passed half way around the pole on the other side thereof and in the same way the ends of the second looped wire may be tightened by twisting. This clamp draws the split or cracked portions of the pole together and binds them firmly in place. In order to pass the 20 wires around the pole in the method described, I have found that it can be easily done after the through-bolt 16 is put into place, but before it is clamped tightly in place, by forcing the channels 25 away from the pole a sufficient distance to allow the passage of the wire between the pole and the channels. This is possible because the channel sections are more or less flexible or resilient. Obviously, some other form of clamping means 30 may be used, such as metal bands, rods, or other suitable encircling member or members which can be readily anchored either to the through-bolt or to the channels. After these clamping wires are secured in place, the through-bolt is 35 tightened, thus forcing the spacers against the wires and the pole and firmly bonding the whole structure together.

For the purpose of providing a finish to the top of each of the channels, I provide a nose piece 40 or cap 23 on each of the upper spacers 14b (see Fig. 7). This cap forms a pleasing finish to the top of the channels and likewise protects against accidents due to persons coming in contact with the sharp upper edge of the channel. Obviously, 45 however, a separate nose piece might be provided and when put in place and not welded or otherwise directly secured to the channel, it could be, by means of bolts or studs, secured by passing such bolts, studs, or screws through holes in the nose piece into the wood of the pole.

In place of the channels herein shown and described, it is obvious that I-beams or other suitably shaped structural sections may, if desired, be used instead of channels with substantially the same effect and efficiency as hereinbefore described.

While I have shown and described a preferred embodiment of my invention, it will be understood that the same is not limited to all the details shown, but is capable of modification and variation within the spirit of the invention and the scope of the appended claims.

Having thus described my invention, what I claim is:

1. The combination with a pole of a plurality of 65 relatively long, narrow, channel sections having their flanges facing the pole, said channel sections being driven into the ground in close proximity to that portion of the pole which is in the ground, said sections having a substantial part 70 of their length disposed within the ground, and their remaining length extending above the ground close to the pole, and a plurality of interspaced through-bolts passing through only those portions of the sections that are above the ground 75 for securing the said sections to the pole at a

plurality of points, whereby a new foundation is created by such sections.

2. The combination with a pole of a relatively long narrow channel, said channel being driven into the ground in close proximity to that portion of the pole which is in the ground, said channel having a substantial part of its length disposed within the ground, and its remaining length extending above the ground close to the pole, sector-shaped spacers secured between the channel and the pole, said channel being so arranged that its flanges face the pole, and through-bolts for securing the said channel and spacers to the pole at a plurality of points only above the ground. 10

3. The combination with a pole of a plurality of relatively long, narrow channels having their right-angled flanges extending toward the pole, said channels being driven into the ground in close proximity to that portion of the pole which is in the ground, said channels having a substantial part of their length disposed within the ground, and their remaining length extending above the ground close to the pole, sector-shaped spacers provided with roughened gripping inside faces secured between the channels and the pole, 15 and through-bolts passing through only those portions of the channels that are above the ground for securing the said channels and spacers to the pole at a plurality of points. 20

4. The combination with a pole of a plurality of relatively long, narrow channels, said channels being driven into the ground in close proximity to that portion of the pole which is in the ground, said channels having a substantial part of their length disposed within the ground, and their remaining length extending above the ground close to the pole, said channels being so arranged that their flanges face the pole, sector-shaped spacers provided with depending portions, each formed with a flat, exterior, central part whereby 30 each spacer may be initially secured to the web of the channel, said spacers being positioned between the channels and the pole and having locking engagement with the channels, and through-bolts passing through only those portions 35 of the channels that are above the ground for securing the said channels and spacers to the pole at a plurality of points. 40

5. The combination with a pole of a plurality of relatively long, narrow channels, said channels being driven into the ground in close proximity to that portion of the pole which is in the ground, said channels having a substantial part of their length disposed within the ground, and their remaining length extending above the ground close to the pole, sector-shaped spacers provided with depending portions, each formed with a flat, exterior, central part and an outwardly extending boss for locking engagement with the channel, whereby each spacer may be initially secured to the web of the channel, said spacers being positioned between the channels and the pole, and through-bolts passing through only those portions 50 of the channels that are above the ground for securing the said channels and spacers to the pole at a plurality of points. 55

6. The combination with a pole of a plurality of relatively long, narrow channels, said channels being driven into the ground in close proximity to that portion of the pole which is in the ground, said channels having a substantial part of their length disposed within the ground, and their remaining length extending above the ground close to the pole, sector-shaped spacers provided with depending portions, each formed with a flat, ex- 60

terior, central part and interiorly extending lugs whereby each spacer may be initially secured to the web of the channel, said spacers being positioned between the channels and the pole, and 5 through-bolts passing through only those portions of the channels that are above the ground for securing the said channels and spacers to the pole at a plurality of points.

7. The combination with a pole of a plurality of 10 relatively long, narrow channels, said channels being driven into the ground in close proximity to that portion of the pole which is in the ground, said channels having a substantial part of their length disposed within the ground, and their re- 15 maining length extending above the ground close to the pole, a cap arranged over the top of each channel, and through-bolts passing through only those portions of the channels that are above the ground for securing the said channels and 20 spacers to the pole at a plurality of points.

8. The combination with a pole of a plurality of relatively long, narrow channels, said channels being driven into the ground in close proximity to that portion of the pole which is in the 25 ground, said channels having a substantial part of their length disposed within the ground, and their remaining length extending above the ground close to the pole, sector-shaped spacers secured between the channels and the pole, a cap 30 arranged over the top of each channel, and through-bolts passing through only those portions of the channels that are above the ground for securing the said channels and spacers to the pole at a plurality of points.

9. The combination with a pole having incipient longitudinal cracks, of a plurality of relatively long, narrow channels, said channels being driven into the ground in close proximity to that portion of the pole which is in the ground, 40 said channels having a substantial part of their length disposed within the ground, and their remaining length extending above the ground close to the pole, through-bolts passing through only those portions of the channels that are above the ground for securing the said channels to the pole at a plurality of points, and a plurality of 45 clamping means associated with the through-bolts and secured to the said through-bolts and arranged between the channels and the pole for securely binding the pole and preventing further 50 extension of the longitudinal cracks.

10. The combination with a pole having incipient longitudinal cracks, of a plurality of relatively long, narrow channels, said channels being driven into the ground in close proximity to that portion of the pole which is in the ground, 5 said channels having a substantial part of their length disposed within the ground, and their remaining length extending above the ground close to the pole, sector-shaped spacers secured 10 between the channels and the pole, through-bolts for securing the said channels and spacers to the pole at a plurality of points above the ground, and a plurality of clamping means secured to the said through-bolts and arranged between the channels and the pole for securely binding the 15 pole and preventing further extension of the longitudinal cracks.

11. The combination with a pole having incipient longitudinal cracks, of a plurality of relatively long, narrow channels, said channels being 20 driven into the ground in close proximity to that portion of the pole which is in the ground, said channels having a substantial part of their length disposed within the ground, and their remaining length extending above the ground close to the pole, upper and lower sector-shaped spacers secured between the channels and the pole, through-bolts for securing the said channels and spacers to the pole at a plurality of points above the ground, 25 and a plurality of clamping means secured to the through-bolt of said upper spacers and arranged between the channels and the pole for securely binding the pole and preventing further 30 extension of the longitudinal cracks, said upper spacers being superimposed over said 35 clamping means.

12. The combination with a pole of a plurality of relatively long, narrow channels having their flanges facing the pole, said channels being driven into the ground in close proximity to that portion of the pole which is in the ground, said channels having a substantial part of their length disposed within the ground, and their remaining length extending above the ground close to the pole, a plurality of interspaced through-bolts 40 passing through only those portions of the channels that are above the ground for securing the said channels to the pole at a plurality of points, and means carried by the channels for 45 protecting the upper edges thereof.

ROBERT L. ALLEN.
